(57) **CLAIM**

The ornamental design for a hanging chair as shown and described.

DESCRIPTION

FIG. 1 is a perspective view of a hanging chair showing the claimed design;

FIG. 2 is another perspective view of a hanging chair showing the claimed design;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of an area labeled 9 in FIG. 1; and,

FIG. 10 is another enlarged view of an area labeled 10 in FIG. 1.

The broken lines in the drawings illustrate the screws, form no part of the claimed design.

The dash-dot-dash broken lines encircling the enlarged views are for annotative purposes only and form no part of the claimed design.
